CLAIM

The ornamental design for a hair clipper, as shown and described.

DESCRIPTION

FIG. 1 is a front, right, and bottom perspective view of a hair clipper, showing our design.

FIG. 2 is a rear, left, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front, right, and bottom perspective view of a body of the hair clipper of FIG. 1.

FIG. 10 is a rear, left, and top perspective view of the body of the hair clipper.

FIG. 11 is a front elevation view of the body of the hair clipper.

FIG. 12 is a rear elevation view of the body of the hair clipper.

FIG. 13 is a left side elevation view of the body of the hair clipper.

FIG. 14 is a right side elevation view of the body of the hair clipper.

FIG. 15 is a top plan view of the body of the hair clipper.

FIG. 16 is a bottom plan view of the body of the hair clipper.

FIG. 17 is a partial enlarged view of an area labeled 17 in FIG. 9 comprising a blade; and,

FIG. 18 is a front, right, and bottom perspective view of the hair clipper shown in an exploded state.

The broken lines shown in the drawings are included for the purpose of illustrating portions of the hair clipper that form no part of the claimed design.

The dash-dot-dash broken lines illustrate the boundary of the enlarged, partial view and form no part of the claimed design.

The body of the hair clipper is disclosed separately for convenience of illustration.
